STOP MECHANISM FOR KNITTING MACHINES

Filed Nov. 3, 1930

UNITED STATES PATENT OFFICE

JACOB WACHSMAN, OF BROOKLYN, NEW YORK

STOP MECHANISM FOR KNITTING MACHINES

REISSUED

Application filed November 3, 1930. Serial No. 493,179.

My invention relates to electric stop mechanisms of the general type disclosed in my application filed January 15, 1929, Serial No. 332,644, and in my Patent No. 1,778,097, issued 5 October 14, 1930.

Primarily the invention has for its object to improve the mechanisms disclosed in my previous application and patent in order to render the operation of the device more positive and in order to reduce friction on the thread to a minimum, and thereby reduce the danger of fraying the thread and possibly causing it to break.

Again, it is an object to provide a gravity actuated lever which will tend to lift the thread off the surface of the spring-held lever arms, thereby to reduce the area of contact between the thread and these parts, instead of having the gravity actuated lever press the 20 thread down on the surface of the spring-held lever arms as in my previous application and patent.

Further, it is an object to provide against the accidental closing of the circuit by a mere 25 slackening of the thread.

Other objects will in part be obvious and in part be pointed out hereinafter.

To the attainment of the aforesaid objects and ends, the invention still further resides 30 in the novel details of construction, combination and arrangement of parts, all of which will be first fully described in the following detailed description, then be particularly pointed out in the appended claims, reference 35 being had to the accompanying drawings, in which:—

Figure 1 is a side elevation of the embodiment of my invention which has been especially designed for use with fine thread, the 40 electric circuit of the stop motion mechanism being diagrammatically indicated.

Figure 2 is a front elevation of the device shown in Figure 1.

Figure 3 is a plan of the same.

Figure 4 is a vertical longitudinal section 45 on the line 4—4 of Figure 3.

Figure 5 is a perspective view of another embodiment which has been especially designed for use with medium weight thread. 50 Figure 6 is a perspective view of a further

embodiment which has been especially designed for use with a heavy thread.

In the drawings in which like numerals of reference indicate like parts in all of the figures, I provide a housing consisting of a 55 supporting plate 1 having a bent over end 2 for mounting and provided with shoulders 3 to constitute stops for limiting the movement of the spring-held lever 13 hereinafter again referred to. The plate 1 is also provided with a cut-away portion 4 while the bent over or mounting portion 2 of the plate is provided with a hole 5 for the reception of a screw or bolt 6 by means of which the device may be mounted on a suitable supporting part of the 60 knitting machine.

The housing also includes a box 7 whose front is closed by the plate 1 and which is secured to that plate by screws or bolts 8. Mounted within the box 7 is a long contact 70 spring 9 and a short contact spring 10 secured to a suitable terminal bolt 11 that is mounted on, but insulated from, the box 7.

Bearing notches 12 are provided in the side walls of the box 7 for the spring-held 75 lever 13 whose parallel arms embrace the plate 1 and extend forwardly thereof, terminating in porcelain fingers 14 having concave portions 15 to hold the thread T. The spring-held lever where it passes through 80 the box 7 is provided with a heel 16 for effecting contact with the springs 10 and 9 when the lever 13 is pulled down against the tension of the hold-back spring 18 as will later be explained. The spring 18 has one 85 end hooked into a stirrup 17 that is carried by the heel 16 and it has its other end anchored to a screw 19 which carries an adjusting nut 19a whereby the tension of the spring may be regulated.

20 designates a gravity actuated lever which is mounted in suitable bearing notches 22 in the side walls of the box 7 and which has a loop portion or heel 21 to engage the contact spring 9 when the lever 20 is raised 95 beyond a certain limit as will later be more fully explained.

The lever 20 has a rearwardly extending portion 23 bent over to underlie a pivoted weight-lever 24 which is also mounted in suit- 100

able bearing notches 25 in the side walls of the box 7 and which has for its purpose to over-balance the lever 20 and continuously tend to elevate it to a position higher than that indicated in dotted lines in Figure 1, whereby when so elevated to the highest position the heel 21 of the lever 20 will engage the contact spring 9 and close the electric circuit. The lever 20 in the first embodiment of my invention has its front end bent into approximately the shape of the letter M thus providing two loops 26 with three parallel rods 27 which lie between the porcelain fingers 14 of the spring-held lever 13 when the thread 15 T is in position, see Figure 1.

28 is the downwardly and forwardly inclined portion of a guard member formed of wire and secured at 6 to the bent over end 2 of the plate 1, the guard member also including rearwardly extending approximately horizontal portions 29 which merge with vertical back stop portions 30, from one of which there is an upwardly and rearwardly extending portion 31 that is anchored at 8 to the plate 1, see Figures 1, 2 and 3. The construction of the guard is such that when the gravity actuated lever 20 is free to rise the portions 29-28 of the guard will pass within the loops 26 between the parallel portions 27, 30 it being understood that the vertical portions 30 continuously lie projected through the loops 26 and between the fingers 14, see Figures 1 and 2.

The portion 31 of the guard which is anchored at 8 is continued laterally as an extension 32 to constitute a stop for limiting the upward movement of the gravity actuated lever 20. By bending the projection 32 up or down (see Figure 2) the height to 40 which the lever 20 may be permitted to rise before engaging the stop 32 may be correspondingly varied.

In the embodiment of my invention shown in Figure 6, those parts which are of the same construction as shown in Figure 1 bear the same reference numerals. Those parts which correspond in construction and function but are different in form from the parts shown in Figure 1 bear the same reference 50 numerals plus the index letter y. In this embodiment (Figure 6) the back stop 33 is formed as a part of the gravity actuated lever 20y instead of as a part of the guard as in Figure 1.

55 In the embodiment shown in Figure 5 those parts which are of the same construction as corresponding parts in Figure 1 bear the same reference numerals and those parts which are of similar construction and perform the same function as corresponding parts in Figure 1, but differ therefrom in form, bear the same reference numerals plus the index character z. In the embodiment of Figure 5 it will be observed that the guard 65 is a single guard and the gravity actuated

lever has but a single loop 26z instead of the double guard and loop structure shown in Figure 1.

The electric stop mechanism which is controlled by my circuit closer may be of the ordinary construction, and as it per se forms no part of the present invention, it has been merely diagrammatically indicated in Figure 1, by reference to which it will be observed that 34 is the battery and 35 the magnet which actuates the stop motion actuating lever 36 to stop the machine when the magnet is energized.

In the use of my invention the device is mounted at a suitable location on the knitting machine and the thread is laid over the two levers 20 and 13 so as to lie in the concavity of fingers 14 as best shown in Figures 1, 2, 4 and 5 of the drawings.

When the thread is running through the machine it is under sufficient tension to hold the gravity actuated lever in substantially the positions indicated in Figures 1, 4, 5 and 6. The gravity actuated lever being overbalanced by the weight-lever 24, continuously tends to raise the thread so as to reduce its frictional contact area with the fingers 14 tending to assume the position shown in Figure 2 but normally not quite reaching that position. When, however, the thread slacks then the position shown in Figure 2 and in dotted lines in Figure 1 will be reached, but the electric circuit will not be closed in the box 7 because the guard 28 overlies the thread T and prevents the gravity actuated lever from raising to its circuit closed position. However, as soon as the end of the thread passes the guard the lever 20 will rise and close the circuit, thus stopping the movement of the knitting machine. Furthermore, if undue tension is put upon the thread as for example if a knot causing a stoppage of the movement of the thread before it reaches the circuit closer, the thread will pull down the levers 20 and 13 and slip off of the same, thereby at once releasing both the levers 13 and 20 and permitting them to close the electric circuit. The arrangement is preferably such that as the lever 13 is pulled down to a position about to release the thread, its heel 16 will make electrical connection with the spring 10 and at once close the circuit to the stop mechanism.

100 The back stops 30, 30z and 33 serve to prevent the thread from working back over the fingers 14 and getting into a position where the thread will tend to bind or meet with undue friction.

105 From the foregoing description, taken in connection with the accompanying drawings, it is thought the complete construction, operation and advantages of my invention will be clear to those skilled in the art to which 110 it relates.

What I claim is:

1. In stop mechanism under control of a travelling thread, a circuit closer unit comprising a housing, a fixed contact member insulated from and mounted in said housing, a circuit terminal therefor, a spring-held lever fulcrumed in said housing and including two substantially parallel arms extending to the outside of said housing, and having a contact heel to engage said contact member when said arms are pulled down, a gravity actuated lever also fulcrumed in said housing and having a contact heel to engage said contact member when said gravity actuated lever is moved upwardly beyond a predetermined position, said gravity actuated lever having its fore end positioned to be held between said parallel arms by the thread placed thereover, and overbalancing means continuously tending to move said gravity actuated lever to bring its fore end above said arms and move it to a circuit closing position.

2. In stop mechanism under control of a travelling thread, a circuit closer unit comprising a housing, a fixed contact member insulated from and mounted in said housing, a circuit terminal therefor, a spring-held lever fulcrumed in said housing and including two substantially parallel arms extending to the outside of said housing, and having a contact heel to engage said contact member when said arms are pulled down, a gravity actuated lever also fulcrumed in said housing and having a contact heel to engage said contact member when said gravity actuated lever is moved upwardly beyond a predetermined position, said gravity actuated lever having its fore end positioned to be held between said parallel arms by the thread placed thereover, and overbalancing means continuously tending to move said gravity actuated lever to bring its fore end above said arms and move it to a circuit closing position, and a guard member mounted on said housing to hold said gravity actuated lever against closing the circuit so long as a thread lies over the fore end of said lever, said guard member also including an upright back stop located between said arms.

3. In stop mechanism under control of a travelling thread, a circuit closer unit comprising a housing, a fixed contact member insulated from and mounted in said housing, a circuit terminal therefor, a spring-held lever fulcrumed in said housing and including two substantially parallel arms extending to the outside of said housing, and having a contact heel to engage said contact member when said arms are pulled down, a gravity actuated lever also fulcrumed in said housing and having a contact heel to engage said contact member when said gravity actuated lever is moved upwardly beyond a predetermined position, said gravity actuated lever having its fore end positioned to be held between said parallel arms by the thread placed thereover, and overbalancing means continuously tending to move said gravity actuated lever to bring its fore end above said arms and move it to a circuit closing position, and a guard member mounted on said housing to hold said gravity actuated lever against closing the circuit so long as a thread lies over the fore end of said lever.

4. In stop mechanism under control of a travelling thread, a circuit closer unit comprising a housing, a fixed contact member insulated from and mounted in said housing, a circuit terminal therefor, a spring-held lever fulcrumed in said housing and including two substantially parallel arms extending to the outside of said housing, and having a contact heel to engage said contact member when said arms are pulled down, a gravity actuated lever also fulcrumed in said housing and having a contact heel to engage said contact member when said gravity actuated lever is moved upwardly beyond a predetermined position, said gravity actuated lever having its fore end positioned to be held between said parallel arms by the thread placed thereover, and overbalancing means continuously tending to move said gravity actuated lever to bring its fore end above said arms and move it to a circuit closing position, and a guard member mounted on said housing to hold said gravity actuated lever against closing the circuit so long as a thread lies over the fore end of said lever.

5. In stop mechanism under control of a travelling thread, a circuit closer unit comprising a housing, a fixed contact member insulated from and mounted in said housing, a circuit terminal therefor, a spring-held lever fulcrumed in said housing and including two substantially parallel arms extending to the outside of said housing, and having a contact heel to engage said contact member when said arms are pulled down, a gravity actuated lever also fulcrumed in said housing and having a contact heel to engage said contact member when said gravity actuated lever is moved upwardly beyond a predetermined position, said gravity actuated lever having its fore end positioned to be held between said parallel arms by the thread placed thereover, and overbalancing means comprising a pivoted member mounted on said housing and a finger on said gravity actuated lever to underlie said pivoted member.

6. In stop mechanism under control of a travelling thread, a circuit closer unit comprising a housing, a fixed contact member insulated from and mounted in said housing, a circuit terminal therefor, a spring-held lever fulcrumed in said housing and including two substantially parallel arms extending to the outside of said housing, and having a contact heel to engage said contact member when

said arms are pulled down, a gravity actuated lever also fulcrumed in said housing and having a contact heel to engage said contact member when said gravity actuated lever is moved upwardly beyond a predetermined position, said gravity actuated lever having its fore end positioned to be held between said parallel arms by the thread placed thereover, and overbalancing means continuously tending to move said gravity actuated lever to bring its fore end above said arms and move it to a circuit closing position, and a guard member including a projection serving as a stop to limit the upward movement of said gravity actuated lever.

7. In stop mechanism under control of a travelling thread, a circuit closer unit comprising a housing, a fixed contact member insulated from and mounted in said housing, a circuit terminal therefor, a spring-held lever fulcrumed in said housing and including two substantially parallel arms extending to the outside of said housing, and having a contact heel to engage said contact member when said arms are pulled down, a gravity actuated lever also fulcrumed in said housing and having a contact heel to engage said contact member when said gravity actuated lever is moved upwardly beyond a predetermined position, said gravity actuated lever having its fore end positioned to be held between said parallel arms by the thread placed thereover, and overbalancing means continuously tending to move said gravity actuated lever to bring its fore end above said arms and move it to a circuit closing position, and a guard member mounted on said housing to hold said gravity actuated lever against closing the circuit so long as a thread lies over the fore end of said lever, said gravity actuated lever having its fore part formed with a plurality of parallel portions adapted to be caused to lie between said arms when a thread is in place, and said guard comprising portions to lie between each pair of said plurality of parallel portions, said guard member including a projection serving as a stop to limit the upward movement of said gravity actuated lever.

50 JACOB WACHSMAN.
